UNITED STATES PATENT OFFICE.

LUTHER L. KNOX, OF BELLEVUE, PENNSYLVANIA, ASSIGNOR TO KNOX PRODUCTS COMPANY, OF PITTSBURGH, PENNSYLVANIA, A CORPORATION OF PENNSYLVANIA.

COMPOUND INSULATED STRUCTURE.

Application filed May 1, 1924, Serial No. 710,357. Renewed April 22, 1927.

In the drawings:

Figure 1 is a front elevation of a refrigerator containing my invention;

Figure 2 is a vertical cross section of the same;

Figure 3 is a horizontal section, looking downward, on the line III—III of Figure 1;

Figure 4 is a plan view, partly in section, of an icebox or ice cream cabinet embodying my invention;

Figures 5 and 6 are, respectively, longitudinal and transverse sections of the form shown in Figure 4;

Figure 7 is a cross sectional view similar to Figure 3 showing a modification, and

Figure 8 is a view of the form shown in Figure 1 turned upside down ready for pouring.

My invention relates to a compound insulated structure, and is particularly desirable for the heat insulating walls of structures, such as cold storage rooms, refrigerators, iceboxes, ice cream cabinets, etc. In the usual construction of such walls, a jacket space is provided therein which has ordinarily been filled by inserting blocks or pieces of insulating material, or is filled with granular material, such as granulated cork, mineral wool, etc. In such structures the inner and outer walls of the jacket space were substantially independent of each other structurally. Where this jacket space was filled with blocks of insulating material, voids were left around the blocks and between them and the jacket walls which allowed some air circulation. In the case of granular material, the material shifted and would settle, leaving spaces for air circulation.

My invention is designed to overcome this difficulty and to greatly enhance the heat insulating value of such walls, and in the preferred form to also make the walls substantially waterproof and acid-proof.

In carrying out my invention, I preferably insert in the jacket spaces blocks or slabs of insulating material, such, for example, as molded cork, and then I fill the spaces between the molded cork and the walls of the jacket spaces with a material which preferably remains of a semi-solid character, and which is also preferably waterproof and acid-proof. This material is preferably heated to liquefy or partially liquefy it, and the material is then preferably poured in to fill all the spaces around

the blocks and between them and the jacket walls.

In order to insure adherence between the plastic cement and the jacket walls, I preferably coat these walls prior to pouring in the plastic cement.

As an example of preferred materials to be used in accordance with my invention, I have coated the inner surfaces of the jacket walls with a solution of coal tar oils. Such material is on the market and is a solution of oils extracted from coal tar in treating it. This coating is applied cold and should be allowed to dry for about four hours before inserting the insulating blocks. This coating is preferably done before the metal sheets forming the walls are assembled and secured in place.

After the walls are formed and the insulating blocks inserted, I preferably heat a bituminous, asphalt or pitch-like material, such as certain bituminous compounds marketed and sold as "enamels" to liquefy it, and then pour this into the jacket space to a sufficient amount to entirely surround and fill the voids between the insulating blocks or slabs and the walls of the jacket space. When such material cools to ordinary temperatures, it remains in a semi-solid condition for an indefinite period. When cold it remains in a semi-solid condition for an indefinite period.

In the drawings Figures 1, 2 and 3 show a refrigerator made in accordance with my invention. In this case 2 represents the side walls, 3 the back wall, 4 the doors and 5 the bottom sheet of the bottom wall of the refrigerator. These walls are shown as made up of metal sheets assembled together and secured in any desirable manner, as by seam-95ing, the doors being formed in a similar manner. The jacket space between the walls is shown as filled with ribbed slabs of molded cork 6, the ribs in any one portion of the space preferably extending in the same direction longitudinally of the blocks. These ribs will properly space the blocks and center them between the jacket side walls, leaving side spaces for the plastic cement. The ribs in the back and side walls are shown as extending vertically, and in Figure 8 I show the assembled refrigerator turned upside down with its bottom end upward and left open previous to inserting the insulating blocks in the bottom jacket por-105110

tion and securing the bottom plate 5 in place. While in this condition the heated and liquefied cement is poured in through the bottom of the refrigerator and flows down along the 5 cork ribs of the blocks in the side and back walls, and also along the ribs in the top, which is now at the bottom. When the voids are entirely filled up to the inner level of the bottom, the cork blocks are inserted in 10 the bottom jacket space and more cement is applied to completely surround the blocks in this bottom jacket space. The bottom plate 5 is then applied and secured in place.

The doors, of course, may be made in a 15 similar manner, the plastic cement being poured or filled in around the block and the cover plate applied and seamed or otherwise secured in place.

In Figures 4, 5 and 6 I show an icebox 20 made in the same general way, the cork slabs having the projecting ribs as in the first form. In this case the device is made in the form of a box 7 with removable covers 8 at the top. This is the ordinary form of 25 ice cream cabinet.

In Figure 7 I show a cross section of a refrigerator similar to that of Figures 1, 2 and 3, except that instead of forming the 30 cork blocks or slabs with ribs thereon, I employ wires or rods 9 to space the plain faced insulating blocks from the inner walls of the jacket space. These wires or rods may be simply loose and laid in place before the cement is filled in, or they may extend 35 around the blocks and secured to each other or to others of the wires. Their sole function is to center the blocks and to provide the side spaces to be filled with the cement.

The claims of this application are limited 40 either to the feature of preliminarily coating the metal walls or of utilizing ribbed insulating blocks or slabs, the broad subject matter of the application with respect to compound wall structures being made the subject 45 matter of my copending application Serial No. 2872, filed January 16, 1925.

The advantages of my invention will be 50 apparent to those skilled in the art, since the free spaces or voids heretofore present in these heat insulating walls are done away with, and their heat insulating value thus increased. The opportunity for voids through which air can circulate is prevented 55 and the construction is improved. Lighter sheet material may be used for the wall structure, and in the preferred form the device is made far more waterproof and acid-proof than ordinary walls.

Various materials may be used for the 60 heat insulating filler blocks or slabs, as well as for the cement employed. The cement may be poured in or otherwise applied. It is preferably of a nature to soften by heat, though it may be of a character to

set and harden by drying or otherwise. The 65 heat insulating material may be at one side of the jacket space with the cement between it and the other wall. The preliminary coating of the inner surfaces of the jacket walls may be used or not as desired, and 70 other changes may be made without departing from my invention.

I claim:

1. A compound coated wall structure having 75 a jacket space, a solid filler in the jacket space, and semi-solid material between the filler and a coated wall of the jacket, said material being semi-solid at normal temperatures and liquefying under heat.

2. A heat insulating wall having a jacket 80 space, a preformed ribbed heat insulating block or slab in the space, and cement filling between the said block and a wall of the jacket space.

3. A heat insulating wall having a jacket 85 space, ribbed preformed heat insulating material therein, and cement filling around the heat insulating material.

4. A compound wall structure including 90 spaced apart wall members having an interior coating thereon, filler blocks between the wall members, and a plastic substance interposed between the filler blocks and the coated wall members.

5. A compound wall structure including 95 spaced apart wall members having an interior coating thereon, a mass of filler between the wall members, and a bituminous compound filling the interstices between the filler and the coated walls.

6. A compound wall structure including 100 spaced apart wall members having an interior coating thereon, a mass of filler in the space between the wall members and held in spaced relation thereto, and a cement 105 around the mass of filler and filling the spaces between the filler and the coated wall members.

7. A compound wall structure including 110 spaced apart wall members having an interior coating thereon, a mass of filler in the space between the coated wall members and held in spaced relation thereto, and a plastic bituminous compound around the mass of 115 filler and filling the spaces between the filler and the coated wall members.

8. A compound wall structure having a 120 wall member, an adherent coating on the wall member, a filler slab spaced from the coated side of the wall member, and a bituminous mass adhering to the coated surface of the wall member and interposed between the coated surface of the wall member and the 125 filler slab.

In testimony whereof I have hereunto set 125 my hand.

LUTHER L. KNOX.
